SPECTACLE FRAME OR THE LIKE

Ralph J. T. Bauer, New York, N. Y., assignor to
American Optical Company, Southbridge,
Mass., a voluntary association of Massachusetts

Application May 8, 1953, Serial No. 24,915

Term of patent 14 years

(Cl. D57—1)

To all whom it may concern:

Be it known that I, Ralph J. T. Bauer, a citizen of the United States of America, residing at New York, in the county of New York and State of New York, have invented a new, original, and ornamental Design for a Spectacle Frame or the like, of which the following is a specification, reference being made to the accompanying drawings, forming a part thereof.

Fig. 1 is a front elevational view of a spectacle frame, showing my new design;

Fig. 2 is a top plan view of the spectacle frame shown in Fig. 1 with the ends of the temples broken away; and

Fig. 3 is a perspective view of the spectacle

frame shown in Fig. 1 with the end of one temple broken away.

The characteristic features of my new design are shown in full lines in the drawings.

I claim:

The ornamental design for a spectacle frame or the like, substantially as shown and described

RALPH J. T. BAUER.
